UNITED STATES PATENT OFFICE.

GEORGE W. SMITH AND WALTER W. BECKER, OF BUFFALO, NEW YORK.

FOUNTAIN-BRUSH.

1,044,278.

Specification of Letters Patent. Patented Nov. 12, 1912.

Application filed November 2, 1911. Serial No. 658,085.

To all whom it may concern:

Be it known that we, GEORGE W. SMITH and WALTER W. BECKER, citizens of the United States, and residents of Buffalo, in 5 the county of Erie and State of New York, have invented new and useful Improvements in Fountain-Brushes, of which the following is a specification.

This invention relates to fountain brushes 10 and more particularly to bath brushes wherein the fountain or shower appliance is detachably secured to the brush to permit the latter to be used with or without the fountain-appliance, as may be desired.

15 One of the objects of our invention is to improve the clamping means by which the fountain-appliance is secured to the brush.

Another object is to improve the construction of the fountain-appliance with a view 20 of effecting a thorough distribution of the water over the entire surface of the brush.

In the accompanying drawings: Figure 1 is a top plan view of the brush, partly in 25 section. Fig. 2 is a side elevation with the handle portion shown in section. Fig. 3 is a bottom plan view with a portion of the bristles removed and the clamping device shown in section. Fig. 4 is a vertical longitudinal section of the clamping device. Fig. 30 5 is a cross sectional view, on line 5--5, Fig. 4. Fig. 6 is a perspective view of the clamping device with the shell removed.

Similar characters of reference indicate 35 corresponding parts in the several views.

1 represents the body or stock of the brush the outer edge of which is provided with a groove 2. Assembled in this groove are two water-supply tubes 3, 4, provided at their outer or front ends with inwardly-extending 40 hooks or lips 5 which are detachably seated in a socket or opening 5¹ located in the edge of the brush-stock 1, so as to hold the front portions of the tubes in place thereon. These tubes conform generally to 45 the shape of the brush-stock and their rear portions terminate in substantially parallel tangs or extensions 6, 7.

At suitable intervals along its lower marginal edge the brush stock is formed with 50 recesses 8 for receiving jet nozzles 9 which project inwardly from the tube-sections 3, 4, and distribute the water therefrom preferably to the inner or base portions of the bristles. At these points the jets issuing 55 from the nozzles meet with the least resist-

ance and the water is therefore projected into the central as well as the marginal portions of the brush, thoroughly distributing it into all parts thereof.

Adapted to be received upon the tangs or 60 rear extensions of the tubes 3, 4, is a head, manifold or Y-connection 10 provided in its front end with sockets 12, 13, which communicate with the inlet chamber 14 thereof. This chamber is provided at its rear end 65 with a hollow screw threaded stem 15 to the projecting rear end of which is applied a screw nut or nipple 16 adapted to receive the customary supply pipe or hose 18. The hollow tangs or extensions 6, 7 of the tubes 70 communicate with the inlet chamber 14, as shown in Fig. 3, while the front ends of the tubes are closed.

Surrounding the connection 10 is a shell, 75 casing or abutment 17 which bears against the contracted rear portions of the tubes 3, 4, the front end of the shell being preferably notched to receive the latter. The closed rear end of this shell is provided with an opening for the passage of the screw stem 80 15, the nipple 16 abutting against said closed end.

Extending forwardly from the connection 10 is a laterally-swinging spring-arm 19 pivoted at 20 and having a downwardly-bent 85 lip 21 which is wedged rearwardly between the converging portions of the tube-sections 3, 4, upon tightening the nipple 15. Said lip thus serves as an anchor which prevents rearward displacement of the connection 10 90 on the tangs 6, 7 and spreads or forces the latter outwardly against the outer walls of the sockets 12, 13 in the connection 10, forming a strong and reliable connection between these parts.

In order to prevent forward deflection of the lip 21 the connection 10 is preferably provided with a hooked lug 22 which overlaps said lip.

As shown in Fig. 3, the outer ends of the 100 sockets 12, 13 are preferably countersunk to receive rubber gaskets 23 which form a water-tight joint between the tube sections and the Y-connection 10.

24 indicates the handle of the brush carrying a ferrule 25 which fits frictionally and 105 removably upon the rear end of the shell, so that it can be readily detached to afford access to the screw nipple 16.

When it is desired to detach the fountain- 110

appliance 3, 4 from the brush, the nipple 16 is removed after which the shell 17 is slid rearwardly off the screw stem 15, thereby exposing the pivoted spring arm 19. The latter is then swung aside to disengage its lip 21 from the tangs 6, 7, whereupon the connection 10 can be withdrawn from the tangs and the tube sections removed from the brush. In thus disconnecting the lip 21 from the tangs, the elastic arm 19 springs upward sufficiently to allow the lip 21 to clear the tangs.

It will be noted that the fountain or shower attachment comprises two separate tubes, the front ends of which have practically a pivotal connection with the brush stock which permits them to be swung freely toward and from the grooved edge of the stock upon removing the shell 17 and the Y-connection 10. There is therefore no necessity for bending or straining the tubes in applying them to the brush, thus avoiding all liability of breaking them or bending them out of their proper shape.

25 We claim as our invention:

1. A fountain brush comprising a brush-stock, separate water-supplying tubes detachably mounted on opposite sides of the brush stock and extending to the front end thereof, said tubes being disconnected at their front ends and terminating at their opposite ends in hollow rearward extensions, and a water supply connection engaging said extensions.

35 2. A fountain brush, comprising a brush-stock, separate water-supplying tubes detachably applied to opposite sides of the stock and extending to the front end thereof each tube being provided at its front end with retaining means engaging the brush stock and at its opposite end with a hollow rearward extension, and a water-supply connection engaging the extensions of both tubes and holding the rear portions of the 45 tubes in place on the stock.

3. A fountain attachment for brushes, comprising a pair of water-supplying tubes adapted to be applied to opposite sides of a brush-stock and terminating in rearward extensions, the front portions of the tubes having inwardly-turned hooks adapted to engage the brush-stock, and means for connecting said extensions to hold the tubes in place on the stock.

55 4. A fountain attachment for brushes, comprising a pair of water-supplying tubes adapted to be applied to opposite sides of a brush-stock and terminating in hollow rearward extensions, the front portions of the 60 tubes having inwardly-turned hooks adapted to engage the brush-stock, and a water-supply connection communicating with and connecting said extensions.

5. A fountain brush, comprising a brush-stock having an opening in its front portion,

two water-tubes provided at their front ends with means interlocking within said opening, said tubes conforming to the edge of the brush stock and terminating in hollow rearward-extensions, a water-supply connection engaging said extensions, and means for clamping the extensions in said connection.

6. A fountain brush, comprising a brush-stock, water-tubes detachably applied to opposite sides of the stock and having rearwardly converging portions terminating in hollow tangs, a water supply connection receiving said tangs and communicating therewith, an anchoring device carried by said connection and engaging between the converging portions of said tubes, clamping means applied to said connection, and an abutment interposed between said clamping means and the converging rear portions of 85 said tubes.

7. A fountain brush, comprising a brush-stock, water tubes detachably applied to opposite sides of the stock and having rearwardly converging portions terminating in hollow tangs, a water supply connection receiving said tangs and communicating therewith, a shell inclosing said connection and bearing at its front end against said tubes, a hollow screw stem extending rearwardly from said connection through the closed rear end of said shell, and clamping means applied to said stem and bearing against the rear end of the shell.

8. A fountain brush, comprising a brush-stock, water tubes applied to opposite sides of said stock and having converging rear portions terminating in tangs, a connection receiving said tangs, a laterally-swinging spring-arm pivoted to the connection and having a part which engages between said converging portions, and means for drawing said part of the spring arm rearwardly against said converging portions to force the tangs outwardly against the walls of 110 said connection.

9. A fountain brush, comprising a brush-stock, water tubes applied to opposite sides of said stock and having converging rear portions terminating in tangs, a connection receiving said tangs, a member carried by said connection and having a lip which engages between and bears against said converging portions, means for holding said lip against deflection, and means for drawing said member rearwardly relatively to the tangs.

10. A fountain brush, comprising a brush-stock, water tubes applied to opposite sides of said stock and having converging rear portions terminating in tangs, a connection receiving said tangs, a spring-arm attached to the connection and having a lip which enters between and bears against said converging portions, a lug carried by said con- 130

nection and overlapping said lip, and means for drawing the connection rearwardly relatively to said tangs.

11. A fountain brush, comprising a brush-
5 stock, tubes applied to opposite sides of the stock and having converging rear portions terminating in hollow tangs, a water supply connection receiving the tangs and having a hollow screw stem at its rear end, a spring
10 pivoted to the connection and entering between said converging portions, a casing

surrounding the connection, and a clamping device applied to said screw stem and bearing against the rear end of said casing.

Witness our hands this 30th day of Octo- 15
ber, 1911.
